(57) **CLAIM**

We claim the ornamental design for the razor handle, as shown and described.

DESCRIPTION

FIG. 1 is a top perspective view of a razor handle; FIG. 2 is a bottom perspective view thereof; FIG. 3 is a top plan view thereof; FIG. 4 is a bottom plan view thereof; FIG. 5 is a right elevation view thereof; FIG. 6 is a left elevation view thereof; FIG. 7 is a front elevation view thereof; and, FIG. 8 is a rear elevation view thereof. The broken lines illustrate portions of the razor handle and form no part of the claimed design.

1 Claim, 5 Drawing Sheets
